Dec. 14/88

Whole No. 1488,

J. Albert Eshleman, of Philadelphia, Penn.
Letters Patent No. 123, dated Nov. 12, 1861.

The schedule referred to in these Letters Patent and making part of the same.

To all whom it may concern,

I certify that I, J. Albert Eshleman, of Philadelphia County of Philadelphia State of Pennsylvania have invented or produced a new and original design for an Ornamental Cravat, and I do hereby declare the accompanying drawing with the following explanation of the same to form a full, clear and exact description of the said design.

In reference to the drawing.

Fig. 1. represents the cravat as it appears when removed from the neck and stretched out.

Fig. 2, illustrating the cravat as it appears when tied into a bow.

One portion of the cravat is composed of a fabric of one color, and the other portion of a fabric of a different color, the two colors employed in the present case being red and black, other colors however may be used to produce the effect desired.

When the cravat is tied the red end is so intertwined with the black end as to produce the variegated bow illustrated in the drawing.

In the present instance the cravat is so tied that the portions a, b, c, of the bow are black, and the portions d, and e, red, the cravat however may be so tied that the latter portions will be black and the former portions red.

In either case the two colors will be so interspersed as to produce

Des. 1488

the desired ornamental bow.

I claim as my design - A cravat composed of a fabric of two different colors, and formed into the ornamental bow represented in and by the accompanying drawing.

In testimony whereof I have signed my name to this specification
in the presence of two subscribing witnesses.

Witnesses.

Charles E. Foster.

Edwin Eshleman.
